(57) **CLAIM**

The ornamental design for an apparatus for key handling, as shown and described.

DESCRIPTION

FIG. 1 is a top, front, and left side perspective view of an apparatus for key handling showing my new design; FIG. 2 is a front elevational view thereof;

FIG. 3 is a top, front, and left side perspective view of the holder portion thereof;

FIG. 4 is a front elevational view of the holder portion thereof;

FIG. 5 is a rear elevational view of the holder portion thereof;

FIG. 6 is an enlarged bottom plan view thereof;

FIG. 7 is an enlarged perspective view of the key identification portion thereof;

FIG. 8 is a front elevational view of the key identification portion thereof, the rear being identical in appearance;

FIG. 9 is an end elevational view of the key identification portion thereof;

FIG. 10 is an opposite end elevational view of the key identification portion thereof; and,

FIG. 11 is a top plan view of the key identification portion thereof.
